UNITED STATES PATENT OFFICE.

EDWARD ELI EAGLE, OF SELMA, ALABAMA.

APPARATUS FOR STORING, MEASURING, AND CUTTING LINOLEUM.

1,411,771.

Specification of Letters Patent.

Patented Apr. 4, 1922.

Application filed April 2, 1921. Serial No. 458,135.

To all whom it may concern:

Be it known that I, EDWARD ELI EAGLE, of Selma, Alabama, United States of America, a citizen of the United States of America, 5 have invented certain new and useful Improvements in or Relating to Apparatus for Storing, Measuring, and Cutting Linoleum, of which the following is a specification.

This invention relates to apparatus for 10 storing, measuring and cutting linoleum, oil cloth and the like of the type constructed with one or more rotary discs or stands for supporting the roll of material, rotary discs or stands for withdrawing and re-rolling the 15 fabric and a movable rail with top carriers which engage the upper ends of the rolls and maintain them in an upright position.

The object of this invention is to provide an improved machine and more especially 20 means for unrolling and re-rolling the fabric.

Apparatus of this type described made in accordance with this invention is characterized in that the movable rail, which engages 25 the upper ends of the rolls and maintains them in an upright position is provided with an adjustable expanding top carrier adapted to engage the top of the hollow centre of the roll to be unwound and an adjustable gripping 30 device for withdrawing and re-rolling the fabric. The machine may be suitably secured to ensure its steadiness.

A cutting device may be disposed upon the machine for cutting the fabric longitudinally, and adjustable gripping devices may be disposed upon one or more supports and upon the disc or stand on which the roll being rewound is disposed for gripping the fabric during re-rolling.

40 Referring to the accompanying drawings:—

Fig. 1 is a front elevation of one form of device made in accordance with this invention.

45 Fig. 2 is a plan of the form of device shewn in Fig. 1.

Fig. 3 is a side elevation of the form of device shewn in Fig. 1.

Fig. 4 is an elevation of the adjustable 50 expanding top carrier shewn in Figs. 1 to 3.

Fig. 5 is a plan of the form of gripping device shewn in Figs. 1 to 3 on the movable rail.

Fig. 6 is an elevation of the form of the

adjustable gripping device on the rewinding 55 rotary disc or stand shewn in Fig. 1.

Fig. 7 is an elevation of a cutter and gripping device for longitudinal cutting.

In the drawings *a* is the base upon which stand supports *b* carrying a top *c*. Between the supports *b* slides a movable rail *d* which is kept in position by guides *e* *f*, disposed thereon which engage the supports *b*. The supports *b* are fitted with racks *g* *g*, and the movable rail *d* is provided with 60 a shaft *h*, pinions *i* *i*, engaging with the racks *g* *g*, and also a wheel *j* by which the movable rail *d* can be raised and lowered.

The movable rail *d* may be counterbalanced by weights *d*' *d*' and is supported by 70 a pawl *k* disposed thereon and adapted to engage the appropriate teeth of one of the racks *g* when the rail is raised or lowered to its required height. The pawl *k* is actuated by a lever *m* to which is attached a 75 brake *n* for checking the descent of the movable rail *d*. For supporting the fabric to be unrolled a rotary support of suitable length *o* provided with an upright or boss not shewn, is disposed upon the base *a*, and an 80 adjustable expanding top carrier *p* is disposed upon the movable rail *d*.

The top carrier *p* comprises a screw threaded support *q* carrying a rotatable base plate *r* and an internally threaded collar *s*, 85 six side plates *t*, hinged at their lower ends to the base plate *r* and at their upper ends to arms *u* which are hinged at their other ends to the collar *s*. The expandible top carrier *p* as shewn in the accompanying drawings has six sides, but it may well be provided with a smaller or larger number if desired the larger number being preferable.

For the re-rolling of the fabric, on a rotary disc or stand *v*, supported by its 95 bosses 15 on the gear wheel 13 which is disposed pivotally upon the base *a* is carried by an adjustable gripping device in the form of an expansible tapering sleeve *v*' and a top carrier gripping device *w* upon the movable rail *d*. On the gripping device *v* are mounted a hub member *x*, of eccentric shape, a jaw member *y*, pivoted against said hub-member and a screw member *z* passing through a collar 2 and adapted to secure 100 the jaw member *y* against the hub-member *x*. The top carrier gripping device *w* is disposed upon a support 3 constructed with 105

a cone-shaped hub-member 4, jaw-member 5 pivoted against said hub-member, and a screw member 6 passing through the said jaw member and said hub-member and secured with a nut 7, the screw member 6 being adapted to hold the jaw-member to the hub-member. The jaws and, if desired, the hub-members of both the gripping devices aforementioned may be provided with 10 teeth.

Disposed upon the base *a* is a driving shaft 8 which passes through a collar 9 in the movable rail *d*. The shaft is rotated by suitable gearing 10 and carries gear wheels 11, 12 15 at its lower and upper ends which engage with gear wheels 13, 14 carried on the support 15 of disc *v* and the support 3 of the gripping device *w*.

The supports *q* and 3 pass through a collar 16 and 17, respectively on the movable rail *d* and are attached to rocking levers 18 and 19 disposed upon the adjacent supports *b* and operated by the handles 20, 21 to raise or lower the gripping devices *p* *w*.

25 The fabric 22 may be passed between the rollers 23 of a measuring machine 24 of known construction during re-rolling.

A vertical straight edge 25 is mounted in the centre of the frame to serve as a knife-guide when the fabric 22 is cut.

Between the gripping devices *v'* and *w* may be disposed adjustably a support 25' and grippers 26 and, between the base *a* and top rail *d* cutters 28, and roller 29 provided 35 with grooves 30 may be disposed for cutting the fabric longitudinally into suitable widths. They may be assembled as shewn in Fig. 7 which also shews how the fabric 22 may be cut as long as the slit 31, the grooves 40 30 serving to keep the cutter 28 true.

The cutter 28 and roller 29 may be secured to the support 27 by screw actuated clamps 32.

In operation, the roll of fabric 22 to be 45 measured and cut is placed upon the rotary support *o* the movable bar *d* is suitably lowered or raised and the fabric secured thereto by the projection thereon passing up into the hollow centre of the roll and the adjustable carrier device *p* which is pressed down 50 into the hollow interior of the roll at its upper end by the rocking lever 18 and handle 20 and is adjusted to the dimensions of the said hollow centre by rotating the carrier *p* 55 round its screw threaded support *q* by which means the side plates *t* are adjusted to the required dimensions. The loose end of the fabric is led between the rollers 23 of the measuring machine and thence to the gripping 60 devices and secured against the cones *v* and *w* by the jaws and screws disposed thereon. The gearing 10 is operated and thereby the gear wheels 11, 12, 13, 14 and so the material is re-rolled, measured and may 65 be cut off at any desired length by a knife

and the straight edge, or by the device for longitudinal cutting.

What I claim and desire to secure by Letters Patent is:—

1. An apparatus for handling linoleum 70 and like fabrics in rolls, comprising a frame, a vertically adjustable rail, means on the frame for supporting said rail, co-acting means on the frame and rail to engage and rotatably support between them a stock roll 75 of said material, co-acting means on the frame and rail to grip and rotatably support a rewound roll of material taken from a stock roll, and means to rotate said latter elements.

2. In a linoleum handling apparatus having mechanism to rewind linoleum from a stock roll onto a rewound roll, means interposed in the path of the linoleum in its travel from the stock roll to the rewound roll 85 to facilitate the cutting thereof, said means comprising a vertical knife guide for use in severing the linoleum in a vertical line, and a horizontally disposed knife for severing the linoleum lengthwise thereof.

3. In an apparatus for handling and cutting material such as linoleum in rolls, comprising means to wind upon a rewound roll material from a stock roll, cutting appliances interposed in the path of the material 95 from the stock to the rewound roll, said appliances comprising a vertical knife guide for use in severing the material crosswise to its length, and a knife disposed to sever the material lengthwise, and means to adjustably mount said latter knife at the desired height.

4. Apparatus for storing, measuring and cutting linoleum and like fabric comprising a frame a movable rail disposed thereon, means on the frame for supporting said rail, said means comprising counterbalancing weights, means for adjusting said rail comprising racks, pawls, pinions and operating wheels, means for supporting a roll of fabric to be unrolled comprising an adjustable expanding member adapted to engage the top of the hollow centre of the roll, means for unrolling and rerolling the material comprising rotary gripping devices upon said 110 frame and movable rail, and means for measuring the material.

5. In a machine for handling linoleum and the like, a frame comprising means to rotatably support a stock roll, means for unrolling material from the stock roll and rewinding it into a "rewound" roll, said means comprising upper and lower rotary elements having means to positively grip the end of the material in the rewound roll, and means 115 other than the rewind roll itself to positively rotate in unison the upper and lower elements to unroll and rewind the material.

6. A machine for handling linoleum and the like as described in claim 5, in which the 130

drive means for the rewind gripping elements comprises a vertical shaft, a driving crank therefor disposed at one side of the machine, and a transmission drive means 5 from said shaft to the upper and lower rotary rewind elements.

7. Apparatus for storing, measuring and cutting linoleum and like fabrics comprising a frame, a movable rail disposed thereon, 10 means on the frame for supporting said rail, means for adjusting said rail, comprising racks, pawls, pinions and operating wheels, means for supporting a roll of fabric upon 15 the frame, means for gripping said roll between the frame and the movable rail means for unrolling and re-rolling the material, means for measuring the material, and means for cutting the material.

8. Apparatus for storing, measuring and cutting linoleum and like fabric comprising a frame, a movable rail disposed thereon, 20 means on the frame for supporting said rail, means for adjusting said rail, comprising racks, pawls, pinions and operating wheels, 25 means for supporting a roll of fabric to be unrolled, comprising an adjustable expanding member adapted to engage the top of the hollow centre of the roll, means for un-rolling and re-rolling the material, means for 30 measuring the material, and means for cutting the material.

9. Apparatus for storing, measuring and cutting linoleum and like fabric comprising a frame, a movable rail disposed thereon,

means on the frame for supporting said rail, 35 means for adjusting said rail, comprising racks, pawls, pinions and operating wheels, means for supporting a roll of fabric to be unrolled, comprising an adjustable expanding member adapted to engage the top of the 40 hollow centre of the roll, means for un-rolling and re-rolling the material, comprising rotary gripping devices rotated by means of shafts and gear-wheels disposed upon said frame and movable rail, means for measuring 45 the material and means for cutting the material.

10. Apparatus for storing, measuring and cutting linoleum and like fabric comprising a frame, a movable rail disposed thereon, 50 means on the frame for supporting said rail, means for adjusting said rail, comprising racks, pawls, pinions and operating wheels, means for supporting a roll of fabric to be unrolled, comprising an adjustable expanding member adapted to engage the top of the 55 hollow centre of the roll, means for un-rolling and re-rolling the material, comprising rotary gripping devices rotated by means of shafts and gear-wheels disposed upon said frame and movable rail, said gripping devices being provided with screw actuated gripping jaws means for measuring the 60 material, and means for cutting the material.

In testimony whereof I have signed my 65 name to this specification.

EDWARD ELI EAGLE.
